UNITED STATES PATENT OFFICE.

JOSEPH DOUZEL, OF YONKERS, NEW YORK, ASSIGNOR TO THE ALEX.
SMITH & SONS CARPET COMPANY, OF SAME PLACE.

DESIGN FOR A CARPET.

SPECIFICATION forming part of Design No. 20,262, dated November 4, 1890.

Application filed October 10, 1890. Serial No. 367,643. Term of patent 3½ years.

To all whom it may concern:

Be it known that I, JOSEPH DOUZEL, a citizen of the United States, residing at Yonkers, Westchester county, New York, have invented 5 a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design consists of the body A and the border B. The body A is composed of groups of shaded and somewhat scroll-shaped leaf forms connected by scroll-like branches. The border B is composed of an inner margin containing gem forms, a middle portion having groups of shaded and somewhat scroll-shaped leaf forms connected by scroll-like branches, and an outer margin of gem-shaped figures.

What I claim as new, and desire to secure 25 by Letters Patent, is—

1. The design for a carpet, consisting of the body A, substantially as shown.
2. The design for a carpet, consisting of the border B, substantially as shown.
3. The design for a carpet, consisting of the body A and the border B, substantially as shown.
